UNITED STATES PATENT OFFICE.

DAVID D. GORDON, OF CHICAGO, ILLINOIS, ASSIGNOR TO MCGILL MANUFACTURING COMPANY, OF VALPARAISO, INDIANA.

LAMP-SOCKET SWITCH.

Application filed April 14, 1921. Serial No. 481,227.

My invention relates to electric switches and has to do more particularly with improvements on the well known Levolier universal lever switch.

5 Heretofore in the said and other switches, porcelain bases and caps have been in general use for mounting the switch mechanism, contacts and lamp receptacle. Porcelain has certain disadvantages in that the parts are 10 inaccurate, there being variations in the dimensions and shapes of the parts although coming from the same mold, due to the uneven contraction and the warping of the parts in cooling and drying. Also, the 15 material is fragile and when cracked, hygroscopic.

One of the features of my invention is the provision of a simpler and cheaper mounting base for the mechanism and parts 20 which is preferably a flat insulation disc preferably of fibre, which is treated to render it non-hygroscopic. Also by the novel arrangement and construction of the mounting plate and parts carried thereby, the elements 25 are more easily assembled and more positively aligned.

Other features of my invention will be more particularly referred to in the ensuing specification and claim.

30 For a better understanding of my invention reference is to be had to the accompanying drawing in which

Fig. 1 is a transverse section through a lamp socket and switch of my invention;

35 Fig. 2 is a transverse cross section along the line 2—2 of Fig. 1;

Fig. 3 is a view of the switch mechanism and some of the adjacent parts showing the actuating lever partly tilted and the switch 40 mechanism in an open position;

Fig. 4 is a view along the line 4—4 of Fig. 1;

Fig. 5 is a perspective view of the switch frame;

45 Fig. 6 is a detail of the lever connecting clip;

Fig. 7 is a section along the line 7—7 of Fig. 1, showing more particularly the method of mounting the contacts on the base to secure a proper alignment of the parts;

50 Fig. 8 is a top view of the flat insulation plate or base with the switch mechanism removed to show more particularly the contact arrangement;

55 Fig. 9 is a detail view of an insulation clip

which spans the switch frame to insulate the switch arm from the frame and also prevent binding of the intermediate bodily floating operating member; and

Fig. 10 is a view of a portion of the frame 60 and several of the parts to show a function of the said insulation clip of Fig. 9.

Referring now more in detail to the device illustrated, it comprises a flat insulation base or disc 12 having a lamp base screw threaded 65 shell 13 and center contact 14 secured to one side of the base. The center contact 14 is in general of the universal resilient construction as shown in Fig. 7, being fastened to the base by an eyelet 15 which passes through the contact and the base, being turned over 70 its end in a counterbore in the opposite face of the base so as to be situated beneath the surface thereof. This center contact 14 has a switch contact extension 16 which passes 75 through a hole 17 in the face and rests under tension against an aligning face 18 so as to automatically align itself with the disc thereby also with the switch mechanism and particularly the contact making arm thereof. 80

Also, in order to more positively align the center contact with the disc or base, I indent it at 19 as shown in Fig. 7, the indented portion setting in the slot 20 thereby not only 85 automatically aligning itself but also preventing displacement or turning thereof.

A second stationary switch contact 21 is also carried by the base plate 12, said contact 21 being of a resilient metal and having a portion 22 for securing it to the base 12, 90 being clamped between the terminal binding post 23 and the base 12 by a screw 24 which threads into the member 23.

Extending from the portion 22 is a resilient portion 25 which connects to the contact 95 end 21 and rests under tension against an aligning face 26 in a slot in the base 12. The fastening portion 22 of the member is depressed across its face like the center contact 14 and rests in a recess in the face of the base 12 so as to be maintained securely in place. It will thus be seen that by means 100 of the aligning depressions or lugs upon the two contact elements and the cooperating depressions in the base 12, together with the 105 aligning faces 18 and 26 which are engaged by the two contacts 16—21, these two contacts may be easily and readily secured to the base and automatically align themselves 110 under tension so as to be properly spaced.

apart and in proper position to receive the switch contact arm.

As to the screw threaded shell 13, this is fastened to the under side of the base plate 12 by means of a horse-shoe-shaped clamping ring 27, this horse-shoe member being of well known construction and having a terminal binding post 28 which extends through the slot 29 in the edge of the base plate 12 so as to receive one of the incoming line conductors.

This base 12 which is made of a suitable sheet insulating material is capable of positive machining as distinguishing from the heretofore used porcelain bases which varied and thus made it difficult to assemble parts thereon, and also required careful adjustment of the parts after being secured in place.

As the material for this base I preferably employ fibre. Plain commercial fibre, however, has been found objectionable due to the warping which will occur. I have found, however, that by treating the fibre so as to render it sufficiently non-hygrosopic that it is acceptable as a base for the mounting of the switch mechanism and other parts, and to this end treat the fibre by applying preferably two coats of a water-proof varnish and baking the same after each coat at a temperature sufficiently low to prevent burning the varnish or the fibre, but sufficiently high to quickly dry the varnish.

The switch mechanism preferably employed in connection with my invention is of the well known universal lever type having a reciprocating snap action contact arm controlled by a manually operated universal lever. This mechanism includes a box-like frame, shown in Fig. 5 in detail, having a base or bottom side 31 and opposite side 32. Side walls 33-34 are also provided having laterally extending pivot studs 35 which carry insulating sleeves 36 (Fig. 2) and support a U-shaped contact arm 37 having forked ends which embrace the pivot sleeves 36. The contact arm is insulated at its pivot point by means of the bushing 36 and in order to insulate it from the side walls 33-34 of the frame I provide a U-shaped insulating member 47 (Fig. 9) which embraces the frame and is placed over the pivot lugs 35 so as to be positioned between the contact arm and frame sides. This insulating yoke also has an extension 48 which serves to prevent binding of the intermediate operating member 39 between the upper and lower sides of the frame as will be hereinafter more particularly pointed out.

In order to properly position the frame on the base 12, I preferably provide one or more lugs 49 on the bottom 31 which enter corresponding depressions in the base.

With the frame in position on the base 12, the screws 51 are inserted through the open-

ings 52 in the ears 53 whereupon the frame is held in proper alignment on the base.

The contact arm 37 has alternate positions as shown in Figs. 1 and 3, Fig. 1 showing the closed position of the switch and Fig. 3 the open position. The contact arm 37 is connected with an operating spring 38 which hooks through an insulation clip 39 that extends through a slot in the end of the contact arm. The other end of spring 38 hooks over the yoke portion of the intermediate bodily floating operating member 39, which member has alternate pivotally hooked extensions 40 adapted to hook over the edges of the upper and lower sides 32-31 of the frame. This member 39 is U-shaped and has laterally extending pivot studs 41 which engage in the holes in the end of the U-shaped pull member 42 so as to be pivotally operated by this member 42 when the lever 43 is actuated.

Lever 43 is connected to the pull member 42 by means of the U-shaped spring clip 44 which hooks through a hole in the connecting link 45 (Fig. 3) and which link passes through a hole in the yoke end of the pull member 42 and is held by the shouldered head as indicated. Lever 43 rests upon a seat formed by the disc 46 so that the lever may be tilted in any direction and also pulled straight out.

Now as to the operation of the device illustrated and assuming the switch is in its closed position as shown in Fig. 1, upon operation of the lever 43 the link 42 is pulled toward the left thereby rotating member 39 about its upper pivot 40 and thus moving the left or yoke end of member 39 upwardly. This movement shifts the position of the left end of operating spring 38 and as soon as it reaches a position beyond the dead center, that is above a line extending from the axis of the contact arm 37 to the point of spring fastening on clip 39, contact arm 37 suddenly snaps upwardly away from the stationary contacts 16-21.

During this operation of the mechanism and when the contact arm 37 has snapped into its upward position as indicated in Fig. 3, upon releasing the lever 43 spring 38 restores the lever, the intermediate operating member 39 and link 42 to the position indicated in Fig. 3 which is alternate to that in Fig. 1.

With the parts shown in open position as in Fig. 3 an actuation of the lever 43, which is shown slightly tilted in Fig. 3, results in an actuation of the parts to snap the switch arm downwardly into its closed position, moving from that shown in Fig. 3 to the position shown in Fig. 1. Likewise continued successive actuations of the lever will effect successive alternate operations of the switch mechanism.

It sometimes happens that due to a stick-

ing of the switch arm in the stationary contacts 16-21, or perhaps due to an improper adjustment of the parts, an excessive pull upon the mechanism when in the position indicated in Fig. 1 is necessary to effect an actuation of the parts. In such case the intermediate member 39 is drawn rearwardly under undue strain in order to place additional tension on the spring 38 to effect an 10 operation of the switch arm. Or it sometimes happened heretofore that due to such unusual operation as just referred to, intermediate member 39 would bind or stick momentarily between the upper and lower 15 walls of the frame.

Now in order to eliminate this trouble and also effect a more positive operation of the parts I have provided the resilient protecting apron 48 which, in the undue operations 20 pointed out above, is engaged by the rear end of the intermediate member as shown in

Fig. 10 thereby preventing a binding or sticking thereof and also allowing the additional movement of member 39 necessary to give additional tension to spring 38 without 25 a sticking of the parts.

What I claim as new and desire to secure by United States Letters Patent is:

In an electric switch having a box frame, a U-shaped arm pivotally straddling said 30 frame and a reciprocable floating operating member for moving said arm movable between opposite sides of said frame; an insulating yoke embracing said frame and insulating the arm from the frame, and having a stop for limiting the movement of said 35 operating member thereon.

In witness whereof, I hereunto subscribe my name this 12th day of March A. D., 1921.

DAVID D. GORDON.
